STRETCH ROLL

Joseph Steiner, Willimantic, Conn.

Application February 21, 1939, Serial No. 257,734

2 Claims. (Cl. 26—64)

This invention appertains to stretch rolls such as are used in conjunction with textile machinery. More particularly a stretch roll is used in conjunction with carding and shearing machines to prevent wrinkles. Customarily the stretch roll is placed in advance of a rotary brush or card roll to stretch the material so it will not be damaged by the brush or card.

The principal object of the present invention is to provide the stretch roll which can be manufactured at a smaller diameter than the rolls now generally in use, thus lessening the amount of friction of the roll with the material.

Another important object of the invention is to provide a stretch roll constructed in such a manner as to permit easy access to the working parts thereof.

In the drawings:

Figure 1 represents a side elevational view of the roll.

Figure 2 is a fragmentary longitudinal sectional view through one end of the roll.

Figure 3 is a fragmentary detailed sectional view through one end of the roll showing the cylinder turned to a different position from that shown in Figure 2.

Figure 4 is an inside elevational view of one of the slats.

Figure 5 is a fragmentary longitudinal sectional view through the intermediate portion of the roll.

Figure 6 is a cross sectional view taken substantially on the line 6—6 of Figure 3.

Figure 7 is a section taken substantially on the line 7—7 of Figure 3.

Figure 8 is an end elevational view of the roll.

Referring to the drawings wherein like numerals designate like parts, it can be seen that the roll consists in construction of a pair of end mounts, each consisting of a base 5, an upright 6 and a tubular collar 7 through which either the drive shaft 8 or the stub shaft 9 extends, depending upon which end of the roll is being considered.

The collar 7 is oversize and the drive shaft 8 does not engage the same. However, the aforementioned mounts each includes side walls 10 and each of the shafts 8 and 9 carries a collar 11 at a point between the side walls 10 and these collars are recessed at diametrically opposite points to receive the tapered ends of the bearing screws 12 which are feedably disposed through the said side walls 10.

A cylindrical cam 13 split as at 14 is provided at each end of the roll, each of these cams being

disposed in telescopic relation with the corresponding collar 7 and having a bolt 15 disposed through its split portion so that the cam can be tightened snugly in position on the collar 7 to prevent self-adjustment and to maintain the cam 13 so disposed that its high point 16 will always be below the shaft 8 or 9 to the end that inward movements of the slats 17 as they ride along the high points of the cam 13 will act to move the other slats in an outward direction, performing the necessary stretching of the material passing over the roll.

The roll proper is made up of any desired number of slats 17, preferably an even number as each slat has a diametrically opposed companion slat which is operated by an interposed gear 31.

As is clearly shown in Figure 5, the numeral 19 denotes the elongated cylinder which slightly inwardly of its ends has the head portion 20 shrunken on or otherwise secured to the ends of the shafts 8 and 9. Thus the cylinder 19 turns with the shaft 8.

At the intermediate portion of the cylinder 19 is the surrounding sleeve 21 which is held in spaced relation with respect to the cylinder 19 by the spacer ring 22. As is clearly shown in Figure 5, the inner ends of the slats 17 are reduced as at 23 and are slidably interposed between the end portions of the sleeve 21 and the cylinder 19, these reduced end portions 23 being provided with inwardly disposed pins 24 threadedly disposed into the same and having smooth inner ends adapted to ride in the slot 25 of the cylinder 19.

As shown in Figure 2, the outer ends of the slats 17 have inwardly disposed members 26 ridable in the slots 27 at the ends of the cylinder 19 and these members 26 are equipped with nuts 28. Thus the slats 17 are slidably mounted on the cylinder 19 and as shown in Figures 6 and 7 the slats are constructed so as to slidably abut each other and form a substantially cylindrical roll.

A rack 29 is inlaid in the inner face of each of the slats 17 and secured in place by screws 30. Companion slats 17 have their racks 29 meshing with a corresponding gear 31. Thus it can be seen that when one slat 17 is being pushed inwardly as it rides on the high point of the cam 13, its rack is transmitting motion by way of its companion gear 31 to the diametrically opposed slats 17 and acting to move the upper slat in a direction toward one end of the roll. Thus with this action on both end portions of the roll mate-

rial passing over the roll will be stretched to the desired extent.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

10 1. In a stretcher roll, a plurality of pairs of opposed slats, cam means for moving the slats successively in a longitudinal direction as the slats move against the cam means, each of the said slats being provided with a rack at its inner

15

side and gears interposed between opposed slats and meshing with the corresponding racks.

2. In a stretcher roll, a plurality of pairs of opposed slats, cam means for moving the slats successively in a longitudinal direction as the slats move against the cam means, each of the said slats being provided with a rack at its inner side and gears interposed between opposed slats and meshing with the corresponding racks, a cylinder on which the slats are movable longitudinally, pin and slot connections between the slats and the cylinder, said cylinder being formed with openings through which the gears are operative in mesh with the corresponding racks.

JOSEPH STEINER. 15
